UNITED STATES PATENT OFFICE.

LOUIS HERMAN SOHN, OF HURON, SOUTH DAKOTA.

FAN.

1,391,517.

Specification of Letters Patent. Patented Sept. 20, 1921.

Application filed June 16, 1920. Serial No. 389,448.

To all whom it may concern:

Be it known that I, LOUIS HERMAN SOHN, a citizen of the United States, and a resident of Huron, in the county of Beadle and State of South Dakota, have invented certain new and useful Improvements in Fans, of which the following is a specification.

My invention is an improvement in fans, and has for its object to provide a fan especially adapted for use with motor vehicles, wherein the fan has blades which are adjustable to vary the inclination of the blades with respect to the axis on which the fan rotates, to permit the fan to be adapted for different weather conditions, and wherein mechanism is provided for permitting said fan to be adjusted from the seat of the vehicle.

In the drawings:

20 Figure 1 is a side view of the improved fan in place on a motor vehicle;

Fig. 2 is a longitudinal vertical section through the fan;

Fig. 3 is a front view of the fan;

25 Fig. 4 is a front view of one of the blades;

Fig. 5 is a section on the line 5—5 of Fig. 2.

The present embodiment of the invention is shown in connection with a motor vehicle, indicated generally at 1, and the improved fan comprises a hub 2 which is mounted on a shaft 3, and the hub carries a pulley 4 which is connected by a belt 5 with a pulley 6 on the motor shaft 7 to drive the fan. 35 The pulley 4 is supported about the hub in spaced relation to the same by means of a plurality of radially arranged fastening pins.

A rim 8 is provided for the fan, and this rim is connected to the hub and held in spaced relation with respect thereto by means of spokes 9.

The fan blades 10, of which there are six in the present instance, are arranged between the spokes and between the hub and the rim. Each of these blades has a shaft 11 extending longitudinally thereof at the center, and the outer end of each shaft is journaled in a bearing bracket 12 secured 45 to the rim, the inner end being journaled in the hub, as indicated at 13. The inner end of each shaft has a pinion 14, and mechanism is provided engaging the pinions for simultaneously adjusting all of the blades.

The said mechanism comprises a series of 55 rack bars 15, one bar for each pinion, and the bars are mounted to slide longitudinally of the hub, being all connected with a collar 16 mounted on the hub. This collar has a pair of annular ribs 17, forming between 60 them an annular groove, which is engaged by the arms 18 of a fork 19.

This fork is pivoted intermediate its ends to a fixed support 20 on the motor bed of the vehicle, and a link 21 connects the outer end 65 of the shaft with a latch lever 22. The latch lever is pivoted to a toothed quadrant 23 held on the body of the vehicle adjacent to the seat, the latch of the lever being held in engagement with teeth of the quadrant by 70 means of spring mechanism, as shown.

In operation, when it is desired to change the pitch of the blades, the lever is released from the quadrant and is moved to swing 75 the yoke 19. The collar 16 is moved longitudinally of the hub, and the rack bars, being integral therewith, rotate the pinions 14, turning the shafts 11 and the blades. Thus all of the blades are simultaneously 80 rotated.

As illustrated in Fig. 5, the radially arranged pins which connect the pulley 4 to the hub constitute a stop element for limiting the forward movement of the collar 16. By reason of the fact that the collar 16 is 85 limited in its forward movement, the blades of the fan are limited in their turning movement and are prevented from turning completely around so as to reverse the air current produced by the fan. 90

I claim:

1. A fan including a rim and a hub of elongated formation, spokes rigidly connected to the rim and to the forward portion of the hub, blades having pivot elements connected to the rim and the hub, a collar slidably and rotatably mounted on said hub rearwardly of said blades, and having racks slidable on said hub, pinions mounted on said pivot elements and engaged by said racks, whereby the movement of the rack results in the rotation of said blade, a pulley surrounding the said hub and racks, and having radial pins connected to said hub, said collar being provided with a 100 groove, and a lever having branches extending into said groove for moving said collar longitudinally on said hub, said radial pins

constituting a stop element for limiting the forward movement of the racks and the turning of the blades.

2. A fan including a hub, blades having 5 pivot elements connected to the hub, a collar slidably and rotatably mounted on said hub, and having racks arranged about the hub, pinions mounted on said pivot elements and

engaged by said racks, a pulley surrounding said hub in spaced relation to the same and having attaching means connected to said hub and constituting stop elements for limiting the movement of said collar and the turning of said blades, and means to adjust the collar on said hub.

LOUIS HERMAN SOHN.
